MOISTUREPROOF CONTAINER WITH
FLEXIBLE SEAL COVER

Neil S. Waterman, Tarrytown, N. Y.

Application July 23, 1949, Serial No. 106,441

5 Claims. (Cl. 220—24)

1

This invention relates to new and useful improvements in moisture-proof transparent containers with flexible seal covers for displaying and holding various objects such as tablets, pills, watches, etc.

There are certain tablets and pills which are hygroscopic. These hygroscopic tablets and pills cannot be packaged in tin containers with unsealed covers, and other containers of the type used to hold aspirin tablets, milk of magnesia tablets, etc., because containers of this type are not moisture-proof. Therefore, it is customary to package hygroscopic tablets and pills in containers provided with moisture-proof stoppers or caps. It is also customary to place a piece of absorbent cotton in the mouths of such containers to further protect the pills and tablets from moisture.

One of the dominating objects of this invention resides in the construction of a container and cover which in shape bears some resemblance to the usual tin container and cover in so far as they are flat and easily carried in pockets and purses, but which is moisture-proof so that it may be used for hygroscopic tablets and pills. Furthermore, it is proposed that said container be constructed of transparent material in order to also display its contents.

More particularly, it is proposed to characterize the new container by the fact that it is, or may be, made of rigid material, preferably a rigid type transparent plastic. It is proposed that said container be provided with an open side having an outwardly projecting flange which has an end portion, or a corner portion, formed with rounded edges and the remaining portion of said flange having square edges. It is proposed to provide this container with a new flexible seal cover extending across its open side, and said cover having a fairly rigid section formed with a square edge groove engaging said square edge portion of said projecting flange for tightly mounting said cover on said container in a moisture-proof condition. It is further proposed that said cover be provided with a fairly rigid end section, or corner section, formed with a round edge groove engaging upon said rounded edge portion of said projecting flange for releasably connecting these parts. An important object of this invention resides in providing said cover with a thin flexible wall portion integral with the corner or end section and the remaining section of the cover for flexibly connecting said sections of the cover together in order that said corner section, or end section of said cover may

2

be forced to open said container. It is furthermore proposed that the inner walls of said grooves extend into the open side of said container in positive plug fit fashion to moisture seal said container and cover.

It is proposed that the flexible seal cover be made of polyethylene, or other materials which are flexible or flexible at least in thin sections of about .020". Another such material would be nylon. The seal cover could also be made of rubber. Preferably, the container is made of polystyrene.

It should be clearly understood that the dominating objects of this invention are obtained without limiting the container, or the flexible seal cover, to any particular shape, contour, or size.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front elevational view of a moisture-proof container with a flexible seal cover constructed in accordance with this invention.

Fig. 2 is an end view of Fig. 1.

Fig. 3 is a fragmentary enlarged sectional view taken on the line 3—3 of Fig. 2.

Fig. 4 is a sectional view of the bottom portion of the container as illustrated in Fig. 3, but shown per se.

Fig. 5 is a fragmentary enlarged vertical sectional view taken on the line 5—5 of Fig. 4.

Fig. 6 is a plan view of the flexible seal cover, per se, this view being taken looking in the direction of the line 6—6 of Fig. 3.

The moisture-proof container with a flexible seal cover, in accordance with this invention, includes a rigid type container 10 preferably formed of polystyrene or other rigid type plastic transparent material, or other rigid material. This container 10 is provided with an open side 11 (see Fig. 4), having a laterally outwardly projecting flange 12. This flange 12 has a corner or end portion 13 formed with rounded edges 14, and the remaining portion 15 of said flange 12 has square top edges 16. In the particular design of the invention shown the corner or end

portion 13 extends from the left along the front and back of the container to a point 17 at each side of the container. The rounded edges 14 extend from the points 17 to the left, while the square top edges 16 extend from the points 17 to the right.

A flexible seal cover 20 extends across said open side 11 of said container 10. This flexible seal cover 20 preferably is made from polyethylene or other flexible material or material which is flexible at least in thin sections. Polyethylene in thick sections is fairly rigid. However, in sections of .020" and less it is fairly elastic and flexible. Said flexible seal cover 20 is provided with a thick and consequently fairly rigid corner or end section 21 formed with a rounded edge groove 22 engaging upon said rounded edges 14 of said flange 12 and releasably connecting said corner section 21 and flange 12 in moisture-proof condition. Said flexible seal cover 20 is also provided with a fairly rigid section 23 formed with a square edge groove 24 engaging upon said square edges 16 of said flange 12 for tightly mounting the cover 20 upon said container 10 in a moisture-proof condition. A thin flexible wall 25 is integral with said sections 21 and 23 of said cover 20 for flexibly connecting said sections 21 and 23 of said cover 20 together in order that said corner or end section 21 of said cover 20 may be bent using the flexible wall 25 as a hinge or pivot and forced open. This thin flexible wall 25 is of a thickness of .020" or less so as to be quite flexible. This thin flexible wall 25 is located upon the outer face of the cover 20. The flexible wall 25 is formed at the side portions of the cover 20 by slits 32 extending down from the top face of the cover to a short distance from the bottom face of the cover 20 and through the side portions of the cover outwards of the outer faces of the grooves 22 and 24 at the junction points of said grooves 22 and 24. A recess 28 is formed downwards of the top face of the cover 20 in the end or corner section 21 and the right side of said recess is aligned with said slits 32. The central portion of said flexible wall 25 extends along said right side of said recess 28.

The rigid section 23 is formed with a recess 27 formed upwards from its outer face in order to decrease the mass of the cover 20. Said recess 28 is formed in the inner face of the end, or corner section 21, for decreasing the mass of the cover 20 and for forming a tray-like opening for supporting one tablet 30 when the section 21 is hinged open. The dot and dash circles in Figs. 1, 2 and 3 indicate tablets 30 housed within the container 10. The inner faces of the grooves 22 and 24 extend into the open side 11 of said container 10 in positive plug-like fashion for sealing said cover 20 upon said container 10. The inside faces of the container 10 are slightly tapered in order to form a tight fit against the upward projecting inner faces of said grooves 22 and 24. The bottom portions of said grooves 22 and 24 are slightly larger than the portions 14 and 16 of said flange 12, while the top portions of said grooves 22 and 24 are smaller than the thicknesses of the walls of the container 10 so that the top portions of said grooves grip the walls of said container along small areas for better sealing the cover 20 upon said container 10. The adjacent faces of the recess 28 and grooves 22 are sufficiently close to form thin walls 34. The points 35 at the ends of said thin walls 34 adjacent the flexible wall 25 stretch and contract when the end or corner section 21 is hinged open.

The operation of the moisture-proof container with a flexible seal cover may be understood from the following:

The end, or corner section 21 of the cover 20 may be forced open by engaging one's thumb upon the projecting edge portion thereof and forcing it downwards. Because the groove 22 has rounded edges engaging the rounded edges 14 of the flange 12 of said container 10, the end, or corner section 21, will readily open. The dot and dash lines 21' in Fig. 3 schematically indicate the section 21 in a partially open condition. The section 21 may be bent down to a fully opened condition in which the tablets 30 may be discharged from the container 10. The container 10 may be closed by bending the end, or corner section 21 upwards to re-engage it in its original position. Because the flexible seal cover 20 is made from polyethylene or other resilient material, and because the inner faces of the grooves 22 and 24 are a tight fit in the container 10, the container 10 will be moisture-proof. The end or corner section 21 hinges about the wall 25 as a pivot. The points 35 of the thin wall 34, adjacent the flexible wall 25, stretch and contract as the end or corner section 21 is hinged open and then closed.

The entire flexible seal cover 20 may be removed from the container 10 by forcing it off of the flange 12. Conversely, the flexible seal cover 20 may easily be engaged in position on the container 10 by merely forcing the flange 12 into the grooves 22 and 24. The container 10 may be used to hold and display tablets, pills, watches, and other articles.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In a moisture-proof container with a flexible seal cover, a rigid-type container having an open side provided with an outwardly projecting flange having a corner portion formed with rounded edges and the remaining portion of said flange having square edges, and a flexible seal cover for said container extending across said open side and having a fairly rigid section formed with a square edge groove engaging upon said square edges of said flange for tightly mounting said cover on said container, said cover also having a fairly rigid corner section formed with a rounded edge groove engaging upon said rounded edges of said flange for releasably connecting said corner section with said flange, the inner faces of said grooves of said cover extending slightly into said open side of said container in plug fit fashion for positive moisture sealing of said cover upon said container, and a thin flexible wall integral with said sections of said cover for flexibly connecting said sections of said cover together in order that said corner section of said cover may be bent and forced open.

2. In a moisture-proof container with a flexible seal cover, a rigid-type container having an open side provided with an outwardly projecting flange having a corner portion formed with rounded edges and the remaining portion of said flange having square edges, and a flexible seal cover for said container extending across

said open side and having a fairly rigid section formed with a square edge groove engaging upon said square edges of said flange for tightly mounting said cover on said container, said cover also having a fairly rigid corner section formed with a rounded edge groove engaging upon said rounded edges of said flange for releasably connecting said corner section with said flange, the inner faces of said grooves of said cover extending slightly into said open side of said container in plug fit fashion for positive moisture sealing of said cover upon said container, and a thin flexible wall integral with said sections of said cover for flexibly connecting said sections of said cover together in order that said corner section of said cover may be bent and forced open, said thin flexible wall being located at the outer face of said cover and formed by slits in the side portions of said cover and by a recess in the central part of said cover.

3. In a moisture-proof container with a flexible seal cover, a rigid-type container having an open side provided with an outwardly projecting flange having a corner portion formed with rounded edges and the remaining portion of said flange having square edges, and a flexible seal cover for said container extending across said open side and having a fairly rigid section formed with a square edge groove engaging upon said square edges of said flange for tightly mounting said cover on said container, said cover also having a fairly rigid corner section formed with a rounded edge groove engaging upon said rounded edges of said flange for releasably connecting said corner section with said flange, the inner faces of said grooves of said cover extending slightly into said open side of said container in plug fit fashion for positive moisture sealing of said cover upon said container, and a thin flexible wall integral with said sections of said cover for flexibly connecting said sections of said cover together in order that said corner section of said cover may be bent and forced open, said thin flexible wall being located at the outer face of said cover and formed by slits in the side portions of said cover and by a recess in the central part of said cover, and said recess being located in said corner section of said cover and being of a sufficient size to form thin walls between the adjacent faces of said recess and said rounded edge groove, said thin walls being sufficiently thin to be able to stretch and contract when said corner section is bent and forced open and closed.

4. In a moisture-proof container with a flexible seal cover, a rigid-type container having an open side provided with an outwardly projecting flange having a corner portion formed with rounded edges and the remaining portion of said flange having square edges, and a flexible seal cover for said container extending across said open side and having a fairly rigid section formed with a square edge groove engaging upon said square edges of said flange for tightly mounting said cover on said container, said cover also having a fairly rigid corner section formed with a rounded

groove engaging upon said rounded edges of said flange for releasably connecting said corner section with said flange, the inner faces of said grooves of said cover extending slightly into said open side of said container in plug fit fashion for positive moisture sealing of said cover upon said container, and a thin flexible wall integral with said sections of said cover for flexibly connecting said sections of said cover together in order that said corner section of said cover may be bent and forced open, said thin flexible wall being located at the outer face of said cover and formed by slits in the side portions of said cover and by a recess in the central part of said cover, and said recess being located in said corner section of said cover and being of a sufficient size to form thin walls between the adjacent faces of said recess and said rounded edge groove, said thin walls being sufficiently thin to be able to stretch and contract when said corner section is bent and forced open and closed, and said cover being made of rigid type plastic which is flexible and elastic in thin sections in order that said thin walls are sufficiently flexible for the corner section of said cover to be forced and bent open using said first named thin wall as a hinge.

5. In a moisture-proof container with a flexible seal cover, a rigid-type container having an open side provided with an outwardly projecting flange having a corner portion formed with rounded edges and the remaining portion of said flange having square edges, and a flexible seal cover for said container extending across said open side and having a fairly rigid section formed with a square edge groove engaging upon said square edges of said flange for tightly mounting said cover on said container, said cover also having a fairly rigid corner section formed with a rounded edge groove engaging upon said rounded edges of said flange for releasably connecting said corner section with said flange, the inner faces of said grooves of said cover extending slightly into said open side of said container in plug fit fashion for positive moisture sealing of said cover upon said container, and a thin flexible wall integral with said sections of said cover for flexibly connecting said sections of said cover together in order that said corner section of said cover may be bent and forced open, and the inner faces of said container being tapered inwards in order that said inner faces of said grooves form a better seal for said cover.
